CAM GRINDING APPARATUS

Herbert A. Silven, Worcester, Mass., assignor to
 Norton Company, Worcester, Mass., a corpora-
 tion of Massachusetts

Application December 27, 1937, Serial No. 181,783

10 Claims. (Cl. 51—101)

The invention relates to grinding machines, and more particularly to a machine for grinding tapered cams on an automobile camshaft.

One object of the invention is to provide a simple thoroughly practical machine for automatically grinding a plurality of cam blanks on an integral camshaft. A further object of the invention is to provide an automatic cycle control mechanism for controlling the feeding movement of the grinding wheel, the positioning movement of the work table, the rocking movement of the cam toward and from the grinding wheel, and the reciprocation of the truing tool to grind successive cam blanks automatically to a predetermined straight or tapered size and contour. Another object of the invention is to provide an automatic hydraulically actuated truing mechanism for truing the periphery of the grinding wheel in timed relationship with the grinding cycle. A further object of the invention is to provide a truing mechanism which is hydraulically actuated and which is adjustably positioned on a fixed part of the machine and arranged so that it may be swivelled to true a frusto-conical surface on the periphery of the wheel so as automatically to produce cams of a predetermined taper, size, and contour. Other objects will be in part obvious or in part pointed out hereinafter.

The invention accordingly consists in the features of construction, combinations of elements, and arrangements of parts, as will be exemplified in the structure to be hereinafter described, and the scope of the application of which will be indicated in the following claims.

In the accompanying drawings, in which is shown one of the possible embodiments of the mechanical features of this invention:

Fig. 1 is a fragmentary front elevation of the grinding wheel slide, showing the base and ways in section, and also showing the truing mechanism partly in section and partly in elevation;

Fig. 2 is a left-hand end elevation of the wheel head and truing apparatus as shown in Fig. 1;

Fig. 3 is a fragmentary detail view, partly in section, on a reduced scale, taken approximately on the line 3—3 of Fig. 1;

Fig. 4 is a fragmentary horizontal sectional view, taken approximately on the line 4—4 of Fig. 1, showing the pivotal adjustment of the wheel guard and truing apparatus;

Fig. 5 is a fragmentary view, on a reduced scale, showing the relationship of the camshaft supporting centers, the camshaft, and the tapered face grinding wheel; and

Fig. 6 is a diagrammatic view showing the piping diagram and the electrical control circuit.

A cam grinding machine has been illustrated in the drawings having a base 10 which supports a longitudinally movable work table 11 (Fig. 6) on the usual flat and V-ways (not shown). The base 10 also supports a transversely movable wheel slide 12 on a V-way 13 and a flat way 14 for a transverse feeding movement toward and from the work supporting table 11. The wheel slide 12 supports a rotatable grinding wheel 15.

The longitudinally movable work table 11 supports a pivotally mounted rock bar 16 which is supported in bearings 17 (only one of which has been illustrated) at its opposite ends on the table 11 and is arranged so that it may be rocked about its axis which is arranged parallel to the axis of the grinding wheel 15. The rock bar 16 is provided with a rotatable headstock spindle (not shown) which carries a headstock center 18. The rock bar also supports a footstock (not shown) having a footstock center 19. The headstock center 18 and the footstock center 19 are arranged rotatably to support a camshaft 20 to be ground.

Master cams and roller

In order that the cams on the camshaft 20 may be ground to a predetermined size and contour, it is desirable to provide a series of master cams 21 for controlling the rocking movement of the rock bar 16 so as to rock the camshaft 20 being ground toward and from the periphery of the grinding wheel 15 and thereby generate a predetermined shape thereon. A plurality of master cams 21 are mounted on the headstock spindle in axial alignment with the axis of the camshaft 20 being ground. A master cam roller or follower 22 is slidably mounted on a rotatable shaft 23 which is rotatably supported in brackets 24 which are formed integral with the headstock. The master cam roller 22 is preferably indexed automatically as the table 11 is moved longitudinally to position the master cam roller 22 opposite the master cam 21 which corresponds to the cam being ground on the camshaft 20. The details of the master cam roller indexing mechanism have not been illustrated since this feature is not considered to be a part of the present invention. For a detailed disclosure of the automatic shifting of the master cam roller, reference may be had to the prior United States Patent No. 1,783,755 to Trefethen and Belden dated December 2, 1930, and also to United States

Patent No. 2,022,178 to Belden and Silven dated November 26, 1935.

The table traverse and wheel feed mechanisms are substantially identical to the arrangement shown in my prior United States Patent No. 2,078,463 dated April 27, 1937, and also similar to that shown in the United States patent to Belden and Silven No. 2,022,178 dated November 26, 1935, to which reference may be had for details of disclosure not contained herein.

Table indexing movement

The work supporting table 11 is traversed or indexed longitudinally, and automatically by means of a fluid pressure system comprising a cylinder 30 which is fixed to the base 10. A piston 31 is slidably mounted within the cylinder 30 and is connected by means of a piston rod 32 with a bracket 33 depending from the table 11. Fluid under pressure may be admitted to either end of said cylinder in a manner shown in the above mentioned prior patent. The admission of fluid to either a cylinder chamber 34 or 35 is controlled by a table controlling or reversing valve 36. Fluid is pumped from a reservoir 40 in the base 10 through a pipe 41 by means of a pump 42 which is preferably motor driven. Fluid under pressure from the pump 42 is conveyed by suitable piping to a main control valve 43 and also to a combined pilot and feed control valve 44.

Wheel feed

The wheel slide 12 may be moved transversely on the base 10 by a wheel feeding mechanism which may be actuated either manually or hydraulically as desired. In the preferred construction the wheel slide 12 is provided with a depending nut 50 meshing with a rotatable feed screw 51 which is rotatably supported in the base 10 and is connected so that it may be rotated manually, as indicated in my above-mentioned prior patent. The feed screw 51 is arranged so that it may be moved bodily in an endwise direction rapidly to move the grinding wheel slide 12 and the grinding wheel 15 either toward or away from the work. This is preferably accomplished by connecting the rearward end of the feed screw 51 with a piston rod 53 which carries a piston 54 slidably mounted within a cylinder 55. The fluid pressure wheel feeding mechanism may be supplemented by a hydraulically operated dash pot feed control mechanism (not shown). This dash pot mechanism may be arranged as shown in the patent to Silven No. 2,023,704 dated December 10, 1935. The dash pot feed control mechanism has not been illustrated in the present application, since this feature is not considered to be a part of the present invention. For further details of the dash pot construction, reference may be had to the above-mentioned patent. By utilizing a dash pot mechanism of this type, the grinding wheel 15 may be advanced rapidly by admitting fluid under pressure into a cylinder chamber 56 to move the wheel slide 12 rapidly up to a position where the grinding wheel is about to contact with the cam being ground. Then the dash pot piston is picked up by the piston rod 53 and the further advance of the grinding wheel 15 in grinding the cam is controlled by the exhausting of fluid from the dash pot cylinder.

In order to move the grinding wheel 15 from contact with the cam 20 after it has been ground to a predetermined size and contour, the admission of fluid under pressure to the cylinder 55 is reversed and fluid is admitted into a cylinder chamber 58. The pilot or feed control valve 44

serves to control the admission of fluid to the cylinder 55 and also serves as a pilot valve to actuate the main control valve 43.

Rock bar actuating mechanism

In order that the master cams 21 may be maintained in operative engagement with the master cam roller 22 during the grinding operation on a cam, a yieldable pressure device is provided which serves yieldably to maintain the master cam 21 in contact with the follower roller 22. As shown in the drawings, the rock bar 16 is provided with an arm 60. A cylinder 61 is pivotally supported on a bracket (not shown) by means of a circular clamping band 62. The cylinder 61 contains a piston 63 which is connected by a piston rod 64 with a stud 65 on the arm 60. A spring 66 surrounds the piston rod 64 and is contained within the cylinder 61 between the piston 63 and a head (not shown) which is fixed in the lower end of the cylinder 61. The spring 66 is compressed to a sufficient extent to maintain the master cam 21 in operative contact with the master cam roller 22 during the grinding operation.

Hydraulic actuation—rock bar

A fluid pressure mechanism is provided to rock the bar 16 to an inoperative position automatically before the table 11 is traversed so that the master cam 21 and follower roller 22 and product camshaft 20 and grinding wheel 15 will be separated before the traversing of the table 11 is started. This mechanism may comprise a fluid pressure cylinder 70 having a piston 71 slidably mounted therein. The piston 71 is connected to a piston rod 72 arranged in contact with the arm 60. When fluid under pressure is admitted through a pipe 73 into a cylinder chamber 74 within the cylinder 70, the piston 71 moves downwardly and contacts the arm 60 to rock the rock bar 16 and separate the master cam 21 from the follower roller 22.

Grinding wheel driving mechanism

The grinding wheel 15 may be driven from any suitable source of power, such as an electric motor 80 mounted on the upper surface of the wheel slide 12. The motor 80 is provided with a rotatable armature shaft 81 which carries a multiple V-groove pulley 82 on its outer end. A multiple V-groove pulley 83 is mounted on the outer end 60 of a rotatable wheel spindle 84 which rotatably supports the grinding wheel 15. The pulleys 82 and 83 are connected by multiple V-belts 85 so that when the motor is started, a rotary motion is transmitted to rotate the wheel spindle 84 and 55 the grinding wheel 15.

Table indexing movement

The table 11 is traversed or indexed longitudinally and automatically by a fluid pressure system, above described, which comprises the cylinder 30 containing the piston 31 which is connected by the piston rod 32 to traverse or index the table 11 longitudinally. The admission of fluid to either the cylinder chamber 34 or 35 is controlled by the table controlling or reversing valve 36. Fluid from the pump 42 passes through a pipe 80, through a pipe 81, into a valve chamber 82 in the valve 36. A pipe 83 is connected between the valve 36 and the cylinder chamber 70. 35 and a pipe 84 is connected between the valve 36 and the cylinder chamber 34. It will be readily apparent from this disclosure that when the table reversing valve 36 is in the position illustrated in Fig. 6, no fluid is admitted to either of the 75

cylinder chambers and the table 11 will remain stationary. The valve 36 is provided with a valve stem 85 which is operatively connected to a manually operable control lever 86 mounted on a rock shaft 87. A short lever 88 is mounted on the rear end of the rock shaft 87 and has a pin 89 engaging a spool shaped member 90 on the valve stem 85. It will be readily apparent from this construction that when the lever 88 is moved in a clockwise direction, the valve stem 85 will be moved toward the left, as viewed in Fig. 6, so as to admit fluid under pressure through the pipe 84 into the cylinder chamber 34 and cause the table 11 to move toward the right (Fig. 6). Similarly, when the valve stem 85 is moved toward the right (Fig. 6), fluid passes through the pipe 83 into the cylinder chamber 35 to move the table 11 toward the left (Fig. 6). The lever 88 is normally held substantially in the position illustrated by means of an arrow point 91 formed on the lower end of the lever 88 which is acted upon by a spring pressed roller 92.

An actuating mechanism is provided for the valve 36 so that the movement of the work supporting table 11 operates to close the valve 36 so that when the table is traversed through a predetermined distance to position the next cam on the product camshaft 20 in operative relation with the grinding wheel 15, the valve 36 is automatically closed to stop further movement of the table. This is preferably accomplished by means of a dog bar (not shown) which is adjustably mounted on the front edge of the table 11. The dog bar carries a plurality of adjustably mounted dogs which are adjusted along the bar to conform with the spacing of the cams on the cam-shaft 20 to be ground. In order that the control lever 86 may be moved in the direction of the movement of the table 11, it is necessary to provide a secondary actuating lever for cooperating with the table dogs. As illustrated in the drawings, a dog lever 95 is pivotally mounted on a stud 96. The lower end of the dog lever 95 is provided with a projecting pin 97 which rides in a cylindrical aperture (not shown) in the lever 86. These parts have not been completely illustrated in detail since the table operating mechanism of my present case is identical with that shown in my prior Patent No. 2,078,463 dated April 27, 1937, to which reference may be had for details of disclosure not found herein. The dog lever 95 is slidably supported on the stud 96 and is arranged to be moved into or out of the path of the table dogs by means of a pivotally mounted lever 98 supported on a stud 99. The lever 98 is actuated in timed relation with the other mechanisms of the machine and is preferably controlled by means of a cylinder 100. A piston 101 is slidably mounted within the cylinder 100 and is connected to a piston rod 102 which is arranged to bear against the lower end of the lever 98. The piston 101 is normally held in its rearward position (Fig. 6) by means of a spring. The dog lever 95 may be thrown out of the path of the table dogs by admitting fluid under pressure through a pipe 103, the admission of which is controlled by the main control valve 43. The lever mechanism for controlling the movement of the table control valve 36 as well as the dog lever mechanism has not been illustrated in detail in the present case since these parts are identical with those disclosed in my prior United States Patent No. 2,078,463 to which reference may be had for details of disclosure not found herein.

75 When the table 11 is indexed longitudinally,

the longitudinal movement thereof continues until a table dog engages the dog lever 95 and rocks the dog lever and, through the connecting parts, the control lever 86, so that the arrow point 91 rides up on the spring pressed roller 92 until the control lever 86 assumes the full line position as shown in Fig. 6, in which position the table control reverse valve 36 is in a neutral or stop position, cutting off fluid under pressure from the cylinder chambers 34 and 35 of the table cylinder 10.

Table pilot valve

After the table 11 has been indexed intermittently for grinding successive cams on the camshaft 20, it is then desirable to shift the table index control valve 36 into a reverse position so that the arrow point 91 rides on the opposite side of the axis of the spring pressed roller 92. This is preferably accomplished by means of a pilot valve 105 which is of a balanced piston type and is normally held in a neutral or central position by means of a spring 106. When the table 11 reaches its end position in its movement toward the left, a depending projection on an adjustable truing dog (not shown) mounted on the table 11 engages the upper end of the pilot valve lever 107 and rocks it so as to move the pilot valve stem toward the right, as viewed in Fig. 6, so as to admit fluid, which enters a valve chamber 108 from a pipe 109 into a pipe 110 which passes fluid under pressure into a valve chamber 111 at one end of the table reversing valve 36. This pressure moves the valve stem 85 so that the control lever 86 and the arrow points 91 pass over the high point on the spring pressed roller 92 and shift the valve 36 into a reverse position, so that after automatically truing the grinding wheel 15, the table 11 is ready either for an intermittent traversing or indexing movement in a direction toward the right, as viewed in Fig. 6.

Wheel truing mechanism

In a machine of this type, it is desirable that the grinding wheel be trued automatically in between operations so that a trued grinding wheel face will be presented at the start of each grinding operation. It is desirable to provide a truing apparatus which is entirely independent of the table movement so that it may be independently controlled and regulated.

The common practice in automobile engine design has in the past called for a camshaft in which all of the elements of the surface of the cam lie in parallel planes to the axis of rotation of the shaft. In other words, each cam is spaced or of the same dimensions at each end thereof. In the automotive engine employing such a cam-shaft, it has been found that the tappet engaging the cam is worn away in the path which engages the cam on the camshaft. It is rapidly becoming the standard practice, however, to overcome this difficulty and to provide a tapered cam which engages only one portion of the tappet. The tappet and cam are so arranged that the cam tends to rotate the tappet slowly while in use so that instead of having excessive wear on one portion of the tappet, the cam rotating the tappet causes a more or less uniform wear of the surface of the tappet heads. To accomplish this result, it is therefore desirable to provide a grinding face on the grinding wheel 15 which is slightly tapered, that is, a frusto-conical surface which when brought into engagement with the cam being ground serves to grind a slight taper on the cam being ground. The truing apparatus is,

therefore, preferably arranged so that the path of travel of the truing tool may be adjusted relative to the axis of the grinding wheel 15 so that it may be moved in a path parallel with the 6 grinding wheel for producing straight faced cams or may be swivelled angularly relative to the axis of the grinding wheel so as to produce a slight taper on the face of the grinding wheel which in turn produces a tapered face on the cam being 10 ground.

In the preferred construction, the wheel truing apparatus is mounted on a fixed part of the machine, such as the base 10, or as illustrated in the drawings, on a wheel guard 120 which instead of being carried by the wheel slide 12, as is the usual practice, is fixedly mounted on the base 10 of the machine. The wheel guard 120 is provided with a lower plane surface which rests on a plane upper surface on a transversely 15 adjustable slide 121. A pivot pin 122 is interposed between the lower surface of the guard 120 and the slide 121. The wheel guard 120 is arranged so that it may be clamped in position on the slide 121 by means of clamping screws 123, 20 124, 125 and 126. The screws 123 and 124 pass through an elongated slot 127 in the guard 120 and are screw threaded into the slide 121. Similarly, the screws 125 and 126 pass through an elongated slot 128 in the guard 120 and are screw 25 threaded into the slide 121.

The truing apparatus is preferably rigidly supported on the guard 120 by means of a bracket 130 which is provided with a dovetailed slideway 131 having a reciprocable sliding member 132 carried thereby. The slide 132 serves as a support for a diamond tool holder 133 having a truing tool 134 mounted in the lower end thereof (Fig. 2). The truing tool holder 133 is provided with a threaded aperture which meshes with an adjusting screw 135 carried by the housing 136 which is formed integral with the slide 132. An adjusting knob 137 is mounted on the outer end of the screw 135 and serves precisely to adjust the position of the truing tool 134 relative to the slide 132.

45 The diamond truing tool 134 and the slide 132 are preferably arranged for a reciprocatory movement to traverse the truing tool 134 across the face of the grinding wheel 15. The slide 132 is preferably formed as a hollow member which is arranged to slide over a cylinder 138 which is held in a fixed position by a cylinder head and bracket 139 on the supporting bracket 130. A piston 140 is slidably mounted within the cylinder 138. A piston rod 141 is connected at one end to the piston 140 and at the other end to the slide 132. When fluid under pressure is admitted through a pipe 142 into a cylinder chamber 143 at the right end of the cylinder 138, the piston 140, slide 132 and truing tool 134 will move in a direction toward the left (Fig. 1). During this movement, fluid within a cylinder chamber 144 will exhaust through a pipe 145. Similarly, when fluid under pressure is passed through pipe 145 into the cylinder chamber 144, the piston 140, the slide 132, and the truing tool 134 will be moved in a direction toward the right (Fig. 1). The admission of fluid to the cylinder 138 is preferably controlled automatically in 55 timed relation with the automatic cyclic movement of the machine parts by a valve mechanism to be hereinafter described.

To facilitate adjustment of the speed of movement of the truing tool in its travel across the peripheral face of the grinding wheel 15, a suit-

able valve mechanism is provided which in the preferred form, illustrated in Fig. 6, comprises an adjustable throttle valve 146 located in the pipe line 142 and an adjustable throttle valve 147 located in the pipe line 145. By manipulation of the valves 146 and 147, the speed of movement of the truing tool 134 across the operative face of the grinding wheel 15 may be adjusted as desired. Furthermore, by adjustment of these valves, the differential in piston area due to the size of the piston rod within the cylinder chamber 144 may be compensated for so that the truing tool 134 will travel at a uniform rate of speed when it traverses in either direction.

Slow traverse—truing

The normal traversing or indexing movement of the table is comparatively rapid to reduce the loss of time between successive grinding operations on a single work piece. The normal table speed is preferably slowed down before the direction of movement of the table is reversed so as to prevent undue shocks and vibrations of the table. This is preferably accomplished by means of a slow speed valve 150 through which fluid 20 exhausts from the table control valve mechanism. By automatically operating the valve 150 at the end of the table stroke, the passage of fluid through the table indexing mechanism may be throttled to the desired extent to reduce the 25 normal speed of movement of the table 11 to a slow speed desired to eliminate shocks and vibrations when the table 11 is either stopped or reversed. The valve 150 is normally maintained in the position shown in Fig. 6 with the exhaust 30 wide open so that the table 11 may be indexed at a comparatively rapid rate. A spring 151 is connected at one end to a stud 152 carried by the valve casing and at the other end to a stud 153 carried by a downwardly extending arm of 35 a bell crank lever 154. The lower end of the bell crank lever 154 carries a pin 155 which rides in the groove of a spool shaped member 156 carried on the outer end of the valve stem 157. The tension of the spring 151 is sufficient normally to 40 hold the slow speed valve in a normally open or inoperative position.

The bell crank lever 154 is pivotally mounted 45 on a stud 158 and is arranged to be actuated by a collar 159 carried by a vertically movable plunger 160. An adjustable truing dog (not shown) is mounted on the front edge of the work table 11 and serves to actuate the slow speed valve 150 at the desired time in the cycle of operation. The truing dog for operating this 50 mechanism has not been illustrated in the present case since it is identical with that shown and described in my prior United States Patent No. 2,078,463 dated April 27, 1937, to which reference 55 may be had for further details of disclosure not found herein.

The grinding wheel 15 is preferably automatically trued when in a rearward position after all 60 of the cams on a shaft have been ground. A table feed compensating dog (not shown) serves to actuate a pawl and ratchet feeding mechanism 65 (not shown) to cause a rotation of the feed screw 51 to advance the position of the wheel relative to the truing tool just before the truing tool passes across the face of the grinding wheel 70 so as automatically to true the wheel to present a fresh face for the next grinding operation. This mechanism has not been illustrated in the present case since it is not considered to be a part of the present invention, and for further 75

details of construction, reference may be had to the prior United States patent to Belden and Silven No. 2,022,178 dated November 26, 1935.

To facilitate adjustment of the truing apparatus relative to the grinding wheel, the wheel guard 120 which is adjustably clamped to the slide 121 is provided with a nut and screw adjustment comprising a bracket 199 having a nut formed at its upper end which meshes with a screw 198, the inner end of which is rotatably attached to the end of the slide 121. By manipulation of the screw 198, the slide may be adjusted to position the guard and the truing apparatus relative to the periphery of the wheel when desired. The slide 121 may be clamped in adjusted position by gib screws, as indicated in the drawings, so as to lock the guard and the truing apparatus in a predetermined adjusted position.

Main control valve

In a machine of this type, the mechanisms function automatically successively to grind a plurality of camblanks on a camshaft to a predetermined size and contour, and it is essential that all of the mechanisms be properly timed. Inasmuch as most of the mechanisms of the machine are controlled by fluid pressure operated mechanisms, it is desirable to provide the main control valve 43 having a hollow piston contained therein on which are formed a plurality of valve pistons. A spring 165 interposed between a stud 166 carried by the valve casing 43 and a stud 167 carried by a rock arm 168 are pivotally supported on a stud 169. This valve and its operation is identical with that shown in my prior United States Patent No. 2,078,463. Consequently it will not be described in detail herein and reference may be had to the prior patent for details of description not contained herein. Fluid under pressure from the pump 42 passes through the pipe 80 to the main control valve 43 which is in turn arranged to control the admission of fluid under pressure to the table traverse mechanism, the rock bar actuating mechanism, and the truing tool actuating mechanism.

Wheel feed—Cycle pilot valve

In order that the main control valve 43 may be shifted to control the cycle of operation as desired, a valve is provided to actuate the main control valve. In a grinding machine, while the grinding wheel is in grinding contact with the work piece, there is more or less spring in the various parts of the machine. Any sudden change in direction of movement of the moving parts of the machine or the sudden shifting of fluid pressure within the system may be sufficient to set up a vibration which causes the wheel to vibrate and thereby produce inaccuracies in the work piece. It is, therefore, desirable that the grinding wheel be removed from operative contact with the cam being ground before the longitudinal shifting of the table 11 or the shifting of the rock bar 16 to an inoperative position. This is preferably accomplished by utilizing the grinding wheel feed control valve 44 as a control valve to control the admission of fluid to the wheel feed cylinder 55 and also to serve as a cycle pilot valve, whereby fluid under pressure passes through the pipe 80 into the feed control valve chamber 170. In the position of the parts as illustrated in Fig. 6, fluid under pressure passes out through the pipe 171 into a valve chamber 172 at the right-hand end of the main control

valve 43 and serves to move the main control valve 43 into the position illustrated in Fig. 6.

A spring 173 serves normally to hold the wheel feed valve 44 in a position toward the right (Fig. 6) so that fluid under pressure entering the feed control and pilot valve chamber 170 passes out through the pipe 171 into the wheel feed cylinder chamber 55 to cause a rearward movement of the grinding wheel 15. When the main control valve 43 is moved into the position illustrated by fluid passing through the feed control valve 44, fluid is exhausted from a chamber 174 at the left-hand end of the valve 43, forcing fluid out through a pipe 175, through a valve chamber 176 in the wheel feed and cycle pilot valve 44, and out through a pipe 176 into the reservoir 40.

An electric solenoid 180 is provided for actuating the valve 44 in one direction. The armature of the solenoid is pivotally connected to the lower end of a rock arm 181 which is pivotally supported by a stud 182. A pin 183 carried by the upper end of the rock arm 181 rides in a spool shaped member 184 carried by the valve stem 185 of the valve 44. When the solenoid 180 is energized to shift the wheel feed cycle pilot valve 44 into a reverse position, fluid under pressure from the pipe 80 entering the valve chamber 170 passes through the pipe 175 into wheel feed cylinder chamber 55 to cause a forward feeding movement of the grinding wheel 15 and at the same time passes fluid under pressure through the pipe 175 into the end chamber 174 of the main control valve 43 to move the control valve toward the right (Fig. 6). This movement of the main control valve 43 serves to admit fluid under pressure to the various mechanisms of the machine. The solenoid 180 is preferably connected, in a manner to be hereinafter described, to control the movement of the wheel feed valve 44 which in turn controls the admission of fluid to shift the main control valve 43 after a predetermined time in the grinding cycle.

Cycle control mechanism

In order to obtain the maximum efficiency of the machine, it is desirable to provide a suitable cycle control device which serves, after a cam has been rotated through a predetermined number of rotations in operative contact with the grinding wheel, to actuate the main control valve 43 and thereby admit fluid under pressure to the cylinder chamber 14 to rock the master cams 21 and product camshaft 20 away from the master cam roller 22 and the grinding wheel 15, respectively, and to admit fluid to the cylinder chamber 55 to move the grinding wheel 15 rearwardly to an inoperative position and then to admit fluid under pressure to the table traverse cylinder 30 automatically to index the table 11 to present the next cam on the camshaft 20 to be ground into operative relation with the grinding wheel 15. This is preferably accomplished by means of a cycle control counting device or mechanism 190 which is contained within a rectangularly shaped box on top of the bracket 24. This cycle control counting device is identical with that shown in my prior Patent No. 2,078,463. Consequently it has not been shown in detail herein, nor will any attempt be made to describe the details thereof. For details of disclosure of this mechanism, reference may be had to my prior patent above referred to.

This cycle control counting device 190 serves to actuate a mercury tube switch 191 after a predetermined grinding operation has been com-

pleted, which serves to energize a relay 192. The energizing of the relay 192 in turn closes a circuit to energize the solenoid 180 so as to shift the cycle pilot-wheel feed valve 44 and thereby admit fluid under pressure to shift the main control valve 43 toward the right.

Work rotation

The headstock spindle, as represented by the headstock center 18 (Fig. 5), may be rotated by any suitable driving mechanism such as, for example, an electric motor drive, as shown in my prior Patent No. 2,078,463 dated April 27, 1937, and the prior patent to Belden and Silven No. 2,022,178 dated November 26, 1935, to which reference may be had for details of disclosure.

Truing apparatus—Control valve

It is desirable that the truing tool 134 be passed across the periphery of the grinding wheel 15 at least by one complete reciprocation of the tool relative to the wheel face, and also that this truing operation occur in timed relationship with the grinding cycle, and preferably after all of the cams on the camshaft 20 have been ground to the predetermined size and contour, so that a fresh wheel face is provided for grinding the next camshaft. In order to simplify the fluid pressure mechanism, the slow speed valve 150 may be utilized to control the admission of fluid to the truing apparatus cylinder 138. The truing valve 150 is provided with a pair of valve pistons 195 and 196. The valve 195, in the position illustrated in Fig. 6, covers the pipe 145 which connects the valve 150 with the cylinder chamber 144 of the truing apparatus cylinder 138. The valve piston 196 covers the pipe 142 which connects the valve 150 with the cylinder chamber 143 of the truing apparatus cylinder 138. At the end of the stroke of the table 11 to the left, the truing dog (not shown) operating on the roller 153 rocks the bell crank 154 in a counterclockwise direction and shifts the valve stem 157 of the slow speed valve 150 toward the right (Fig. 6), thereby causing a slow speed traversing movement of the table 11 and at the same time moving the pistons 195 and 196 toward the right so as to uncover the pipes 145 and 142, respectively, thus connecting the pipes 145 and 142 with the pipe 84 and 83, respectively, which are in turn connected with the table traversing cylinder 38. In this position of the slow speed valve 150, fluid under pressure passing through the valve mechanisms of the table traverse cylinder 38 also is conveyed through the pipes 145 and 142, respectively, to cause a traversing movement of the truing tool 134 across the face of the grinding wheel 15. As illustrated in Fig. 6, when the dog lever 95 is moved out of the path of the table dogs after grinding the last cam on the cam-shaft 20, the valve stem 85 moves toward the right so that fluid under-pressure entering the valve chamber 82 of the table control or reverse valve 36 may pass out through pipe 83 which passes fluid simultaneously to the table traverse cylinder chamber 35 and also through the pipe 142 into truing apparatus cylinder chamber 143 so as to cause the table 11 and the truing tool 134 to move toward the left, as viewed in Fig. 6.

During these movements of the table 11 and the truing tool 134, fluid under pressure is exhausted from the table traverse cylinder chamber 34 and also from the truing tool cylinder chamber 144. When the table 11 reaches the end of its stroke after a setting of the truing dog, the lever

107 is rocked in a counterclockwise direction, which serves to operate the cycle pilot valve 185 to admit fluid under pressure to the right-hand end chamber 111 of the table control reverse valve 36 to shift it into a reverse position toward the left, which in turn serves to admit fluid under pressure through the pipe 84 which simultaneously passes fluid under pressure to the table index cylinder chamber 34 and also to the truing tool cylinder chamber 144 to move the table 11 and the truing tool 134, respectively, simultaneously in a direction toward the right (Fig. 6), making two passes across the face of the grinding wheel 15. The table 11 is then stopped by the table stop dog 94 (Fig. 6) in a loading position. By manipulation of the adjustable throttle valves 148 and 147, the speed of movement of the truing tool 134 may be varied as desired to produce the desired and predetermined surface on the periphery of the grinding wheel 15.

By swivelling the wheel guard 128 as hereinbefore described, the diamond may be caused to move in a path either parallel to the axis of rotation of the grinding wheel 15 or at an angle thereto to produce either a straight faced wheel for producing straight faced cams 28, or it may be swivelled in either direction at an angle thereto to true a frusto-conical face on the periphery of the grinding wheel 15 to facilitate the grinding of tapered cams on the camshaft 20 being ground.

Operation

The operation of this machine will be readily apparent from the description. Assuming the table 11 to be in its extreme left-hand or loading position, the machine is started into operation and successive cam blanks on the camshaft 20 are ground automatically by the mechanism hereinbefore set forth. The table 11 is moved longitudinally into operative position relative to the first cam to be ground. During this positioning movement, the master cam roller 22 is automatically positioned opposite the first master cam 21 and the grinding wheel 15 is then advanced toward the work piece 28. At the same time, the rock bar 16 is rocked to an operative position so that the first master cam 21 is in operative contact with the master cam follower 22. The infeed of the grinding wheel 15 continues until the cam blank 20 has been ground to the required and predetermined size whereupon the cycle control counting device 190 actuates the mercury tube switch 191 to deenergize the relay 192 and the solenoid 180, thereby releasing the compression of the spring 173 which shifts the cycle pilot valve-feed control valve 44 so as to cause first a rearward movement of the grinding wheel 15 and secondly a shifting of the main control valve 43 toward the left (Fig. 6) which in turn serves to cause an indexing movement of the table 11 which serves to admit fluid to rock the bar 16 to an inoperative position and then to cause a longitudinal indexing movement of the table 11 to position the next cam in operative position relative to the grinding wheel and at the same time automatically to position the master cam roller in operative position with relation to the next master cam 21.

This cycle of operation is continued until all of the cams on the camshaft 20 have been ground to the required and predetermined size, after which a table reversing dog 205 rocks the lever 107 to reverse the movement of the table 11. When the table 11 has moved to the left sufficiently, a truing dog actuates the roller 159 which shifts the slow speed-truing apparatus control valve 150

to slow down the table movement and at the same time serves to start a traversing movement of the truing tool 134 across the periphery of the grinding wheel 15, the wheel guard 120 having been 5 previously adjusted so that the truing tool will move in the desired path so as to produce either a straight or a tapered faced wheel, as desired. The truing tool 134 continues its traversing movement until the table operating mechanism above described reverses the table movement whereupon 10 the fluid under pressure passing to the truing tool cylinder 138 is reversed to traverse the truing tool 134 in the reverse direction, after which the machine stops and the finish ground camshaft 20 15 may be unloaded and a new camshaft inserted in the machine.

It will thus be seen that there has been provided by this invention apparatus in which the various objects hereinabove set forth together with many 20 thoroughly practical advantages are successfully achieved. As many possible embodiments may be made of the above invention and as many changes might be made in the embodiment above set forth, it is to be understood that all matter hereinbefore set forth or shown in the accompanying drawings is to be interpreted as illustrative and not in a limiting sense.

I claim:

1. In a grinding machine, a rotatable grinding 30 wheel, a transversely movable wheel slide therefor, a longitudinally movable work table, a longitudinally reciprocable truing tool, each of which is operated by a separate fluid motor, a main control valve in control of the work table and truing 35 tool motors, a feed control valve in control of said wheel slide motor and main control valve, a pilot and reversing valve interposed between the main control valve and the table motor to control the direction of movement of the table, and to control 40 the admission of fluid to said truing tool motor, and a slow speed valve actuated by said table movement to slow down the table at the end of its travel, said slow speed valve being arranged to serve as a stop and start valve for said truing tool 45 motor.

2. In a grinding machine, a wheel slide, a longitudinally movable work table, a rock bar on said 50 table rotatably to support a camshaft, a longitudinally reciprocable truing tool, each of which is operated by a separate fluid motor, a main control valve in control of the work table and rock bar and truing tool motors, a feed control valve in control of said wheel slide motor and main control valve, a pilot and reversing valve interposed 55 between the table motor and main control valve to control the direction of movement of said table motor and said truing tool motor, and a stop and start valve which is actuated by said table movement to control the stopping and starting of said truing tool motor so as to true the grinding wheel automatically at the end of its table stroke after a work piece has been completely ground.

3. In a grinding machine, a wheel slide, a work 60 table, a truing tool, each of which is operated by a separate fluid motor, a main control valve in control of the work table and truing tool motors, a feed control valve in control of said wheel slide and main control valve, and a stop and start valve actuated in timed relation with the table 65 movement to stop and start truing tool motor.

4. In a grinding machine, a wheel slide, a rotatable grinding wheel on said slide, a work table, a truing tool, each of which is operated by a separate fluid motor, a main control valve in control 70 of the work table and truing tool motors, a feed

control valve in control of said wheel slide and main control valve, a stop and start valve which is actuated in timed relation with the table movement to stop and start said truing tool motor, and means angularly to adjust said truing tool and said truing tool motor so that its path of travel is either parallel to or at an angle to the axis of said wheel.

5. In a camshaft grinding machine, a rotatable grinding wheel, a wheel slide, a work table, a rock 10 bar thereon rotatably to support a work piece, a truing tool, each of which is operated by a separate fluid motor, a main control valve in control of the work table and rock bar and truing tool motors, a feed control valve in control of the wheel slide and main control valve, a stop and start valve which is actuated by said table movement automatically to start and stop said truing tool motor to true said wheel when the table reaches the end of its stroke.

6. In a camshaft grinding machine, a rotatable grinding wheel, a transversely movable wheel slide, a longitudinally movable work table, a rock bar on said table, a longitudinally movable truing tool, each of which is operated by a separate fluid motor, a main control valve in control of the work table and rock bar and truing tool motors, a feed control valve in control of said wheel slide motor and said main control valve, a stop and start valve which is actuated by said work table automatically to true said grinding wheel at the end of the table stroke, and means to adjust the path of travel of the truing tool and the truing tool motor to an angle relative to the axis of said grinding wheel so as to true a frusto-conical face on said 35 wheel.

7. In a grinding machine, a base, a rotatable grinding wheel, a transversely movable slide, a wheel guard surrounding said wheel and fixed relative to said base, a longitudinally reciprocable 40 trueing tool on said guard, a fluid operated piston and cylinder on said guard which are operatively connected to reciprocate said truing tool, and a swivel connection between said guard and base whereby the path of travel of the truing tool is either parallel to or at an angle to the axis of the grinding wheel.

8. In a camshaft grinding machine, a rotatable grinding wheel, a transversely movable slide therefor, a longitudinally movable work table, a rock bar thereon rotatably to support a camshaft, means including master cams and a follower to rock said bar to grind a cam blank to a predetermined contour, means to feed said grinding wheel transversely to grind a cam blank to a predetermined size, means automatically to index said table longitudinally to grind successive cam blanks, and means automatically to true said wheel after a camshaft has been ground comprising a longitudinally movable truing tool, a fluid pressure operated piston and cylinder to reciprocate said tool, and a valve actuated by and in timed relation with said table indexing movement to control said truing apparatus.

9. In a camshaft grinding machine, a rotatable grinding wheel having a frusto-conical operative face, a transversely movable wheel slide therefor, a longitudinally movable work table, a rock bar on said table rotatably to support a camshaft to be ground, means to move said wheel slide transversely to grind successive cams on said shaft, means intermittently to index said table longitudinally, a longitudinally reciprocable truing tool, means including a piston and cylinder automatically to reciprocate said truing tool in timed 70 75

relation with said table indexing movement, and means angularly to adjust the path of movement of said truing tool so as to produce a frusto-conical face on said wheel.

- 5 10. A grinding machine comprising a work support, a grinding wheel support, a grinding wheel mounted thereon, mechanism for effecting relative transverse and longitudinal movement between said supports, means for effecting said

longitudinal movement intermittently to position said grinding wheel and successive portions of the work piece in operative relation, a wheel dressing device mounted independently of said work support, means for reciprocating said wheel dressing device, and means operated by the work support, for initiating the operation of the wheel dressing device.

HERBERT A. SILVEN.
